UNITED STATES PATENT OFFICE.

JOHN J. WAHL, OF CHATTANOOGA, TENNESSEE.

DESIGN FOR A BOX.

Application filed October 12, 1922. Serial No. 3,950. Term of patent 3½ years.

To all whom it may concern:

Be it known that I, JOHN J. WAHL, a citizen of the United States, residing at Chattanooga, county of Hamilton, and State of Tennessee, have invented a new, original, and ornamental Design for Boxes, of which the following is a specification, reference being had to the accompanying drawing, forming part thereof.

I claim:

The ornamental design for a box as shown.

JNO. J. WAHL.
